LIQUID-FUEL BURNER.

1,386,994.

Specification of Letters Patent.

Patented Aug. 9, 1921.

Application filed April 3, 1917. Serial No. 159,448.

To all whom it may concern:

Be it known that we, WILLIAM A. DOBLE, WILLIAM A. DOBLE, JR., and JOHN A. DOBLE, citizens of the United States, and residents 5 of the city and county of San Francisco and State of California, have invented a certain new and useful Liquid-Fuel Burner, of which the following is a specification.

The invention relates to a burner for 10 liquid hydrocarbon fuels and is particularly adapted for use in connection with the boilers of steam propelled automobiles, domestic water heaters and comparable devices.

An object of the invention is to provide 15 a liquid fuel burner which will produce perfect combustion of the fuel.

A further object of the invention is to provide means for igniting the fuel at the burner.

20 Another object of the invention is to provide means for properly proportioning the amount of fuel and air fed to the burner.

The invention possesses other advantageous features, some of which, with the foregoing, will be set forth at length in the following description, where we shall outline 25 in full that form of the invention which we have selected for illustration in the drawings accompanying and forming part of the present specification. In said drawings, we have shown one specific form of our generic invention, but it is to be understood that we do not limit ourselves to such form, because the invention as expressed in the claims may 30 be embodied in a plurality of forms.

Referring to said drawings:

Figure 1 is a vertical section, partly diagrammatic, of one form of the burner of our invention.

40 Fig. 2 is a cross section of a modified form of burner.

Fig. 3 is a cross section of a modified form of burner in which the air current is produced by a rotating element from which the 45 fuel is discharged.

The burner of our invention contains features which particularly adapt it for use in connection with the boilers of steam-driven automobiles, domestic water heaters 50 and devices wherein gas is at present used as fuel. It produces a hot, clean flame in which the mixture of fuel and air is such that the flame will not attack the material of the boiler or other device in which it is used.

The burner is constructed so that a large 55 amount of explosive mixture of air and fuel is not present, thereby eliminating backfiring and is so constructed that the flame does not vibrate, thereby eliminating the whistling noise so common in prior burners. 60 It is also flexible in control, that is, the flame ceases as soon as the fuel is shut off and the fuel ignites immediately after the fuel is turned on. The burner is also constructed so that it may be started on a light fuel and 65 after it becomes heated, the supply of light fuel may be cut off and heavy fuel used. It is highly important in liquid fuel burners wherein a mixture of air and fuel is discharged by the burner, that the mixture 70 ignite immediately as it begins to emerge, since otherwise, the boiler, water heater or other device, becomes charged with a highly explosive mixture, which, when it ignites, explodes with destructive violence. It is 75 also advantageous from an economical standpoint, to be able to extinguish the flame immediately when it is no longer required. The burner of our invention possesses all of these advantageous features. 80

In one of its embodiments the burner comprises an air chamber 2, preferably annular in shape, but which may be of any desired shape, into which air is forced by a suitable blower or other device. For many uses, the 85 annular burner is advantageous and we have illustrated and will describe an annular burner, but it is to be understood that we do not limit ourselves to such form. The air inlet pipe 22 is preferably tangentially disposed with relation to the air chamber, so that the air is given a rotary motion in the chamber equally distributing the fuel to all parts of the burner. At its lower inner portion in the annular construction, the air 90 chamber is provided with an annular trough 3. Engaging the upper wall of the air chamber 2 and extending downward into the trough 3 is a blade or ring 4 which, with the outer wall 5 of the trough 3, forms a 95 narrow, annular passage through which the air passes. Arranged within the ring 4 and spaced apart therefrom, and having its outer wall 6 substantially parallel with the adjacent face of the ring 4, is a circular plate 100 7 which is filled with refractory material 8 against which the flame is directed. The plate 7 is spaced from the inner wall 9 of the

trough 3 by a ring of electric insulating material 10. The ring 4 is beveled to a sharp edge at its lower edge and this edge lies adjacent the bottom of the trough, so that during the operation of the burner the air is whipped around the sharp edge. The liquid fuel is introduced into the trough 3 above the lower edge of the blade and in being carried around the edge of the ring by the rapidly moving air, is effectively broken up. The particular type of burner, embodying the trough or cup, and the blade extending into it, is not claimed in this application. In Fig. 1 we have shown two pipes 12 and 13 for the introduction of fuel into the trough and these pipes may be used for the same fuel or one may be used for a light fuel and the other for a heavy fuel. The light fuel is used for starting and after the burner becomes heated, the heavy fuel may be substituted. The air and liquid fuel are fed to the burner in substantially constant proportions and in the proper proportion to produce the proper combustion. Connected to the shaft of the air blower 24 are fuel measuring devices such as small plunger pumps 25 and 26 which are arranged in the fuel lines 12 and 13 respectively, and these devices vary the amount of fuel flowing in proportion to the speed of the blower. The lines 12 and 13 are provided with valves 27 and 28 for opening and closing the lines and these may be operated manually to shift from light fuel to heavy fuel when the burner becomes hot. Automatic means may be employed when desired for shifting the fuel supply from light to heavy fuel and vice versa. Arranged in the lines 12 and 13 are valves 31 and 32 which are connected to a thermostatic device 33 which is in thermal communication with the burner. The thermostat is so connected to the valves 31 and 32 that the movement of the thermostat due to its increasing temperature, opens valve 32 and closes valve 31, thereby substituting the heavy fuel for the light fuel when the burner is hot. When the burner is cold, valve 31 is open and valve 32 is closed.

After being whipped around the sharp, lower edge of ring 4, the fuel mixture passes up through the annular mixing chamber 14, which is narrow and of small volume, so that the volume of explosive mixture present at any time is small and the liability of backfiring overcome. The upper edge of the ring 4 is provided with an inwardly and downwardly turned flange 15, which, with the flange 16 on the edge of the plate 7, forms a narrow, annular nozzle from which the flame discharges toward the refractory material 8. The flame is directed inward from the edge toward the center of the burner when the annular construction is employed. The plate 7 is provided with a central aperture 17 through which the fire can be observed and

through which additional air may be allowed to pass to complete the combustion, if it is necessary, a transparent damper 34 of mica or similar material being provided for that purpose.

After the burner has been in operation for a time, the plate 7 becomes heated and since the plate forms one wall of the mixing chamber, the carbureted mixture in the mixing chamber is heated and a more efficient mixture is produced.

Means are provided for igniting the mixture at the nozzle. The opposite sides or walls of the nozzle are insulated from each other and are closer together than other insulated parts of the burner, so that when an E. M. F. is applied to the insulated parts, a spark or plurality of sparks discharge across the aperture of the nozzle and ignite the mixture. Since the nozzle is elongated the sparks jump across the aperture at different parts of the nozzle and travel along the nozzle, thereby insuring instantaneous and complete ignition. Any suitable means, such as a spark coil 18 provided with a vibrator 19, may be employed in parallel with the motor 21 which drives the air blower for producing the necessary sparks, but when an electric motor is not employed for driving the blower, the ignition current may be derived from a storage battery.

In the construction shown in Fig. 2, the burner is provided with two nozzles, 35 and 36, each of substantially the same construction as the nozzle shown in Fig. 1, the nozzle 35 being arranged as the nozzle in Fig. 1 and the nozzle 36 being arranged at the center of the burner and being adapted to direct the flame outwardly toward the refractory material 8 which is so designed that the flame from either nozzle will not impinge on the other nozzle. In this construction, the nozzle 36 is used for light fuel, the flame from which heats the burner to a sufficient degree before the fuel is started through the nozzle 35, and for this reason nozzle 36 only has insulated parts across which the ignition spark jumps.

In the construction shown in Fig. 3 the fuel is fed through the shaft 37 onto the rotating disk 38 which is provided with vanes 39 on its under side. Arranged below the disk is a circular element 41 which terminates adjacent the edge of the disk in an insulated ring 42 which is connected to one side of a sparking coil. Arranged above the periphery of the disk and adjacent thereto, is a stationary insulated ring 43 connected to the other side of the sparking coil. The oil fuel is thrown by the disk in a fine spray through the slot between the disk and the ring 43 and the air current issues from the slot between the disk and the ring 42 and the air atomizes the spray and produces an explosive mixture which is ignited by the spark

which jumps the gap between the insulated rings 42 and 43 which form the nozzle.

We claim:

1. In a liquid fuel burner, a nozzle formed of two parts electrically insulated from each other and forming the nozzle opening, and means for causing an electric spark to bridge the nozzle opening.
2. In a liquid fuel burner, a nozzle formed of two insulated plates spaced apart from each other, means for causing an electric spark to bridge the gap between said plates, and means for blowing a mixture of air and fuel through said nozzle, the mixture being adapted to be ignited by the electric spark.
3. In a liquid fuel burner, a narrow, elongated nozzle formed of two parallel electrically insulated plates between which an igniting electric spark may be formed.

4. In a liquid fuel burner, a nozzle, means for blowing air through said nozzle, an electric motor for driving said blowing means, a conduit for introducing fuel into the air stream, a fuel-measuring device in the fuel conduit connected to the air-blowing means, spark terminals on opposite sides of the nozzle, said motor and spark terminals being connected in parallel, whereby a plurality of sparks across the nozzle are provided when the motor circuit is closed. 30

In testimony whereof we have hereunto set our hands at San Francisco, California, this 15th day of March, 1917.

WILLIAM A. DOBLE.

WILLIAM A. DOBLE, JR.

JOHN A. DOBLE.
